[57] **CLAIM**

The ornamental design for a sectionalized panel and cowl for covering a windshield, as shown and described.

DESCRIPTION

FIG. 1 is a top, left side isometric view of a sectionalized panel and cowl for covering a windshield showing our new design;

FIGS. 2 and 3 are respective front and left side elevational views thereof; and

FIGS. 4 and 5 are respective top plan and bottom plan views.

The side opposite to that shown in the drawing is substantially a mirror image thereof.

The cab structure as shown in broken lines is not a part of the design sought to be patented and is shown for illustrative purposes only.

FIG 2FIG 5
